UNITED STATES PATENT OFFICE

THOMAS MACCALLUM, OF NORTH LIMA, OHIO

SECTIONAL TRACK

Application filed September 9, 1929. Serial No. 391,256.

This invention relates to an apparatus for mining coal, an object being to provide means whereby thin seams of coal heretofore left unmined due to the cost of mining, may 5 be mined at a profit.

Another object of the invention is the provision of a novel form of conveyor apparatus which may be used for the above stated and other purposes, in which the conveyor may 10 be conveniently and readily moved as the position of the work changes.

Another object of the invention is the provision of an apparatus which includes power operated cars or pans, the construction or 15 arrangement of which will permit of their operation to the use of a minimum amount of power.

With the above and other objects in view, the invention further includes the following 20 novel features and details of construction, to be hereinafter more fully described, illustrated in the accompanying drawings and pointed out in the appended claims.

In the drawings:—

25 Figure 1 is an enlarged fragmentary sectional view of a portion of the conveyor track and illustrating the manner of connecting the adjacent ends of the track or rail sections.

30 Figure 2 is an enlarged transverse sectional view taken through the joint of the track sections.

Figure 3 is a longitudinal sectional view of the same.

35 Figure 4 is an enlarged fragmentary transverse section through one of the rails, illustrating the connection between the rails and the spacing bars.

40 Figure 5 is a detail perspective view of one of the spacing bars for the track.

The apparatus which is designed to convey coal to the cars to be taken from the mine, comprises a track 14.

45 The track 14 is formed of rail sections 17 of angular cross section. These rail sections are arranged as shown in Figure 4 of the drawings and their adjacent ends are connected by means of bars 18. For this purpose, the ends of the rail sections 17 are pro-

vided with lugs 19 which are spaced from and parallel with the rail sections. The lugs and rail sections are connected by pins or rivets 20 which bridge the space between these lugs and rail sections.

The connecting bars 18 are substantially 55 U-shaped in cross section and are provided with spaced slots 21 which receive the pins 20 so that when the connecting bars 18 are engaged over the lugs 19 as shown in Figures 4 and 5 of the drawings, the rail sections 60 17 will be held against relative longitudinal and lateral movement. The bars 18 may be provided with horizontally disposed flanges 22 which rest upon the surface of the ground and act to stabilize the rails. 65

The opposed faces of the rails are provided with offset straps 23 which define with the rail sections, pockets 24. These pockets receive the rightangled ends 25 of spacing bars 26 which connect the rail sections and hold 70 the rails in proper relative spaced position.

It is to be noted that the character of the rails which form the track 14 is such that they may be laid and maintained in proper 75 position without the use of spikes, while the track may be conveniently moved when it is necessary to change the position of the conveyor by disconnecting the rail sections and moving the same upon opposite sides of the shoring timbers or posts 38 without moving 80 these posts.

By reference to the foregoing description and accompanying drawings, it will be seen that the conveyor may be constructed to suit all conditions without material increase in 85 the cost of operation. Its construction will permit of the motor or other power unit being placed in such position as not to require its removal for several weeks, as the motor is separated from the conveyor and connected 90 by means of a cable. A further and very important advantage resides in the fact that the conveyor need be only one-half the length of the wall. The cost of the conveyor will thus be reduced in proportion to the length of the 95 face of the wall.

The invention is susceptible of various changes in its form, proportions and minor 100 details of construction and the right is herein reserved to make such changes as properly

fall within the scope of the appended claims.

Having described the invention what is claimed is:

1. A sectional track of angular cross section rails, spacing bars having their opposite ends removably engaged therewith, lugs spaced from and parallel with the rail sections at opposite ends thereof, pins connecting the lugs and rail sections, and means removably positioned over the lugs of the ends of adjacent track sections and engaging the pins to detachably connect the sections.

2. A sectional track of angular cross section rails, spacing bars having their opposite ends removably engaged therewith, lugs spaced from and parallel with the rail sections at opposite ends thereof, pins connecting the lugs and rail sections, transversely U-shaped bars removably positioned over the ends of adjacent track sections and having slots to receive the pins to detachably connect the track sections.

In testimony whereof I affix my signature.
THOMAS MACCALLUM.
